United States Patent Office

Des. 191,592
Patented Oct. 17, 1961

191,592

NAPKIN HOLDER

Bern E. Wolf and James H. Lee, Los Angeles, Calif.,
assignors to Prestige Hardware Corporation, Industry,
Calif., a corporation of California

Filed May 11, 1961, Ser. No. 65,116

Term of patent 14 years

(Cl. D44—24)

FIG. 1 is a front perspective view showing the napkin holder of our design;

FIG. 2 is a rear perspective view;

FIG. 3 is a front elevational view;

FIG. 4 is a top plan view;

FIG. 5 is a side elevational view; and

FIG. 6 is an enlarged, fragmentary section as indicated by the line 6—6 on FIG. 3.

We claim:

The ornamental design for a napkin holder, as shown.
